UNITED STATES PATENT OFFICE.

LOUIS JORDEN, OF SAN FRANCISCO, CALIFORNIA.

LUBRICATING DEVICE.

1,383,212.

Specification of Letters Patent. Patented June 28, 1921.

Application filed March 22, 1921. Serial No. 454,503.

To all whom it may concern:

Be it known that I, LOUIS JORDEN, a citizen of the United States, residing in the city and county of San Francisco and State of California, have invented a new and useful improvement in Lubricating Devices, of which the following is a specification.

My invention relates to improvements in lubricating devices for lubricating carpenters' saws and the like, wherein a lubricant retainer is normally arranged to retain a suitable lubricant, such as a strip of fresh pork fat or the like, within a housing and operates in conjunction with means for exposing the said lubricant whereby the same may be applied or dispensed to a saw or other tool blade, requiring lubrication, by attrition.

The primary object of the present invention is to provide a new and improved lubricating device for saws and the like.

A further object of the invention is to provide a new and improved lubricating device for saws and the like having means for detachably retaining and dispensing a solid lubricant.

Another object is to provide a new and improved device of the character described having improved means for automatically preventing contact of the lubricant, when not in use, with other articles or materials to prevent contamination or soiling of said lubricant as well as soiling of other adjacent articles, and also to provide a lubricating device which may be carried within a pocket of the operator without soiling said pocket or said lubricant.

I accomplish these and other objects by means of the improved device disclosed in the drawings forming a part of the present specification wherein like characters of reference are used to designate similar parts throughout the said specification and drawings, and in which:

Figure 1 is a plan view of my improved lubricating device, the same being disclosed in operative position.

Fig. 2 is a longitudinal vertical sectional view, partly broken, of Fig. 1.

Fig. 3 is a view similar to Fig. 2 but disclosing the manner in which the lubricant

retainer is detached for the purpose of renewing said lubricant.

Fig. 4 is an enlarged transverse sectional view taken on line 4-4 of Fig. 2 in the direction indicated; and

Fig. 5 is a transverse sectional view taken on line 5-5 of Fig. 2 in the direction indicated.

Referring to the drawings the numeral 1 is used to designate in general a hollow semi-cylindrical housing having a handle 2 longitudinally disposed upon one end thereof.

Rotatably mounted within the housing 1 is what I term a detachable lubricant retainer 3 beveled at one end as at 4 to facilitate insertion of said end under a stirrup 6 of a transverse member 7 having a square shank 8 adapted for detachable engagement with a rotary member 9 mounted within the handle 2 and provided with a pinion 11 in mesh with a transversely disposed rack 12, in turn operatively connected to an operating or actuating arm 14 pivotally mounted upon the handle 2 as at 16 by means of which arm 14 said rack and pinion 11 and 12 respectively, may be actuated to rotate said member 7 and the lubricant retainer 3, detachably connected thereto, for the purpose hereinafter more fully set forth.

The opposite end of the retainer 3 is provided with a reduced portion 17 which is detachably connected by means of a spring member 18 to a second transverse member 19 also rotatably mounted within the opposite end of the housing 1 by means of a suitable pin or trunnion 21.

A suitable spring 22 is interposed between the arm 14 and the adjacent side of the handle 2 to normally retain the lubricant retainer 3 in an inoperative position, or with the solid lubricant 23, such as a strip of fat or the like, on the inner side of said retainer 3 to prevent exposure and contact of said lubricant, when not in use.

A laterally disposed pin 24 is provided on the member 7 to limit the rotative movement of the lubricant retainer 3.

In operation the spring 22 actuates the arm 14, rack 12, pinion 11, and lateral member 7 to normally retain the lubricant re-

tainer 3 in an inoperative position or with said solid lubricant 23 on the inner side of said retainer 3, to prevent exposure and contact of said lubricant when in the pocket or tool chest of the user, the pin 24 resting upon one side of said housing 1 to hold said retainer 3 in such inoperative position.

In order to rotate the retainer 3 to bring the lubricant 23 outermost or to expose the same whereby it may be dispensed by attrition onto a saw blade or the like, the arm 14 is depressed which operates the rack 12, pinion 11 and member 9 with the square shank 8 detachably inserted therein, and thereby rotates the lubricant retainer 3 through approximately one-half of a revolution and exposes the lubricant 23 outermost or on the outside of the housing 1, the pin 24 limiting the movement. The arm 14 is held depressed to retain the lubricant in such exposed or dispensing position while the entire device is moved longitudinally over a saw blade or the like with the lubricant 23 in contact therewith.

Release of the arm 14 permits the spring 22 to acuate the several parts as hereinbefore mentioned and the retainer 3 is thus automatically returned to normal or inoperative position with the lubricant 23 innermost or on the inside of the retainer 3 and housing 1.

Having thus described my invention, what I claim as new and desire to secure by Letters Patent is:

35 1. A lubricating device for saws and the like comprising a housing; a lubricant retainer rotatably mounted within said housing; means for normally retaining said lubricant retainer in an inoperative position 40 within said housing; and means for rotating said lubricant retainer to expose a lubricant thereon outside of said housing.

2. A lubricating device for saws and the like comprising a housing; a lubricant retainer rotatably mounted within said housing with the lubricant thereon on the inside of said retainer; and means for reversing said retainer to expose the lubricant thereon whereby said lubricant may be dispensed.

45 3. A lubricating device for saws and the like comprising a hollow semi-cylindrical housing; a retainer rotatably mounted within said housing and arranged to retain a lubricant, such as a strip of fat, on the inside of said retainer; and means for reversing said retainer to expose said lubricant on the outside of said housing whereby said lubricant may be dispensed.

55 60 4. A lubricating device for saws and the like comprising a hollow semi-cylindrical housing; a retainer rotatably mounted within the housing and arranged to detachably retain a strip of fat on the inside of said retainer; and means for reversing said re-

tainer to expose said fat on the outside of said housing whereby said fat may be dispensed by attrition.

5. A lubricating device for saws and the like comprising a hollow semi-cylindrical housing; a retainer rotatably mounted within the housing and arranged to detachably retain a lubricant on the inner side of said retainer; means for reversing said retainer to expose the lubricant thereon; and means for normally retaining said retainer with the lubricant side innermost.

6. A lubricating device for saws and the like comprising a housing; a lubricant retaining device rotatably mounted within said housing; means for normally retaining the lubricating side of said retainer within said housing; and means for reversing said lubricant retainer to expose the said lubricating side outermost whereby said lubricant may be dispensed.

7. A lubricating device for saws and the like comprising a housing; a lubricant retaining device rotatably mounted within the housing; a pinion operatively connected to the lubricant retainer; a rack operatively connected to the pinion; and means for actuating the rack to rotate the retaining device and expose a lubricant thereon outermost whereby said lubricant may be dispensed.

8. A lubricating device for saws and the like comprising a housing; a lubricant retaining device rotatably mounted within the housing; a pinion operatively connected to the lubricant retainer; a rack operatively connected to the pinion; means for actuating the rack to rotate the retaining device and expose a lubricant thereon outermost whereby said lubricant may be dispensed; and means for normally actuating the rack and pinion to normally retain the lubricating side of said retainer within said housing.

9. A lubricating device for saws and the like comprising a housing; a lubricant retainer rotatably mounted within the housing and arranged to detachably engage a lubricant such as a strip of fat; a handle extending from one end of the housing; a pinion rotatably mounted within said handle and arranged to detachably engage said retainer; a rack operatively connected to the pinion and arranged to rotate the same; and an arm pivotally mounted upon the handle and operatively connected to the rack whereby said pinion may be actuated to rotate the retainer and expose the lubricant side of said retainer outside of the housing.

10. A lubricating device for saws and the like comprising a housing; a lubricant retainer rotatably mounted within the housing and arranged to detachably engage a lubricant such as a strip of fat; a handle extending from one end of the housing; a pinion rotatably mounted within said handle and

arranged to detachably engage said retainer; a rack operatively connected to the pinion and arranged to rotate the same; an arm pivotally mounted upon the handle and 5 operatively connected to the rack whereby said pinion may be actuated to rotate the retainer and expose the lubricant side of said

retainer outside of the housing; and means for normally actuating the arm to retain the lubricant side of the retainer within the 10 housing.

In witness whereof I hereunto set my signature.

LOUIS JORDEN.
